T. J. STEARNS.

CARPET.

No. 16,063.

Patented Apr. 28, 1885.

UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 16,063, dated April 28, 1885.

Application filed April 2, 1885. Term of patent 3½ years.

To all whom it may concern:

Be it known that I, THOMAS J. STEARNS, of Boston, in the county of Suffolk and State of Massachusetts, have invented a certain new and useful Design for Carpets, of which the following is a specification.

The nature of my design is fully shown in the accompanying photographic illustration.

The design is composed of the ground ornamented by rectangles of Grecian border-work, with center-pieces within the squares, and floral and foliage ornamentation partly concealing the ground ornamentation.

I claim—

The design for a carpet, substantially as is shown and described.

In testimony whereof I have signed my name to this specification, in the presence of two subscribing witnesses, this 31st day of March, 1885.

THOMAS J. STEARNS.

Witnesses:

DAVID MCNAIR,
